UNITED STATES PATENT OFFICE

CLARENCE H. CHUBBUCK, OF BALA-CYNWYD, PENNSYLVANIA, ASSIGNOR TO HASLETT CHUTE AND CONVEYOR COMPANY, OF OAKS, PENNSYLVANIA, A CORPORATION OF PENNSYLVANIA

CHUTE DOOR CONTROL

Application filed February 21, 1930. Serial No. 430,218.

My invention relates to the inlets for chutes such, for example, as are required at different floors of buildings in the use of trash chutes, laundry chutes, etc.

5 The main purpose of my invention is to secure simplicity of construction along with positiveness and reliability of action.

A further purpose is to provide cooperating chute doors with interfitting disc locks, 10 each of which is cut out to allow movement of the other in one position.

A further purpose is to provide projections movable with one door which fit into the path 15 of movement of a member movable with the other door.

Further purposes will appear in the specification and in the claims.

I have preferred to illustrate my invention by but one main form, selecting a form which 20 is practicable, efficient and inexpensive and which at the same time well illustrates the principles involved.

Figure 1 is a vertical section taken upon line 1—1 of Figure 2, showing the chute entrance fully with a fragment of the chute to 25 which it forms entrance.

Figure 1a is a fragmentary section on the line 1a—1a of Figure 1.

Figure 2 is a front elevation of the structure seen in Fig. 1.

Figures 3 and 4 are enlarged fragmentary sections showing structure seen in Figure 1, but in different positions.

Figure 5 is a diagrammatic view corresponding generally to Figure 3; and Figure 6 is a similar view corresponding to Figure 4.

In the drawings similar numerals indicate like parts.

40 In chute constructions of the character which are intended to permit inlet at different floors or levels, and at the same time protect against outlet of dust or fumes from the chute, it is customary to use two chute doors, 45 of which one closes off the mouth of the inlet and the other closes the connection between the inlet hopper and the body of the chute.

Various conflicting and expensive constructions have been proposed to interconnect these 50 two doors so that one only can be opened at

a time, in order that in all positions of the doors there may be a seal against emission of dust, fumes or flame through the inlet. There are several devices of this character at present on the market which secure the result 55 but with an expense of equipment which is objectionable.

My invention is intended to secure the same end with a minimum of complication and expense.

60 The front chute wall 5 is shown in fragmentary form. The inlet chute hopper 6 is connected with it at the top at 7 and at the bottom at 8 and comprises the body of the hopper 9 and a housing 10 within which the doors 11 and 12 are hinged about rods 13 and 14 and which holds and protects the interlocking mechanism. The connection at 7 may desirably be through the use of a channel yoke 7' secured in the wall structure. A 65 door opening handle may be seen at 13'.

The hopper 9 may be of any suitable form, and it, the chute, the connections with the chute and the housing are intended to be illustrated conventionally.

75 The fastening of the doors to their shafts is conveniently effected by edge-supporting braces 15, 16 rigidly secured to the doors at or near their edges and which are spot-welded or otherwise secured to control discs 17, 18, preferably two for each rod, which may be fastened to swing with the rod or free to swing about it as desired. Each door thus swings as a unit with the two terminal discs upon the rod or about its rod. For the reason that I desire ordinarily to use thicker and stiffer material for the braces 15 and 16 than is necessary for the doors I prefer to use separate braces rather than to form the braces as flanges from the edges of the doors. Flanges 19, 20 on the members 15 and 16 may be used to better secure the doors to the braces, preferably by spot-welding as at 80 points 21.

85 The construction of the housing is not intended to involve any special features as it may be greatly varied, providing it performs the function of affording movable support for the two shafts or rods at or near the ends of the shafts, and at all times affords a 90 95 100

cover to prevent flow of gas from the chute.

In the illustration the housing is provided with side closing and shaft supporting walls 22, top and front walls 23 and 24 and partition 25.

5 The control between the two doors, preventing openings of one when the other is open, is effected by the aligned control discs which are larger in diameter than the distance between their axes and from which corresponding sectors 26 and 27 are cut out to the diameter of the discs. Each sector can be outlined by the movement of a point on the circumference of the other disc when the center of the sector lies between the axes of the 10 two shafts.

15 The upper edges 28 and 29 of the sectors are substantially in line when the doors are closed so that the movement of either door brings the edge and segment adjoining it wholly 20 within the path of movement of the edge of the other disc to prevent motion of the other disc and consequently to prevent movement of the other door. The portion 30 of each disc adjoining the edge of the cut acts as a 25 stop to prevent improper movement of the other door.

25 From Figures 5 and 6 it will be seen that the full surfaces of the discs need not be used for the stop functions since the operative parts of the discs for stop uses comprise the edges 31 and 32 and the arc surfaces 26' and 27' which they are adapted respectively to engage. In the position of Figure 5 the cam 35 18 is free to move in either direction, while the cam 17 is locked in both directions, against opening by the cam 18 and against closing because the door 11 is already closed. In Figure 6 the cam 17 is free to move in 40 either direction, while the cam 18 is locked in both directions, against opening by the cam 17 and against closing by the frame of the door 12.

45 From the diagram in Figures 5 and 6 it will be apparent that a part only of each of the discs of Figures 3 and 4 is effective for stop purposes and that the discs are made in that shape because of conditions of appearance, convenience of manufacture and ease 50 of attachment to or mounting for bearing upon their respective rods rather than because of the usefulness of the remainder of the disc portions. It is for this reason that the discs are referred to in the claims as stops.

55 From Figures 5 and 6 it will be seen that each of the stops will utilize a segment only from point 33 to point 34, but slightly exceeding in its angle 35 the angle 36 of swinging movement intended to be given to its door. 60 No outline or interior limit of the recess 26' or 27' is required, and the remaining circumference of the discs shown is used for the purpose only of affording attachment of the doors.

65 The discs 17 and 18 form convenient means

of attachment of the door structures to the shafts, and the discs can be fastened to the shafts and the door structures can then be secured to the sides of the discs directly, if desired, or permissibly by reinforcing side members 15 and 16.

70 However, neither the discs nor the doors need be secured to the shafts, provided at least one disc is secured to one door and a cooperating disc to the other door.

75 The construction shown for door 12 (best seen in Figure 1a) utilizes flanges 20 turned over from the members 16 for attachment to the door, and shows the outside edge of the door bent over at 33 to lock against the 80 upper edge 34 of the hopper 9.

85 In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

90 Having thus described my invention what I claim as new and desire to secure by Letters Patent is:

1. In a chute inlet, an inlet casing, a pair of chute doors therefor pivoted to swing upon adjacent axes, and controlling stop devices swinging coaxially with the doors and each with opening movement swinging into the path of movement of the other whereby when one has begun to open the other cannot be 100 opened.

2. In a chute inlet, an inlet casing, a pair of doors therein mounted to swing about parallel adjoining axes and cooperating discs carried by the doors having recesses permitting movement of one disc within the recess of the other when the first is closed and stopping movement of each by the circumference of the other when the other is opened.

3. In a chute inlet, a chute wall, an inlet casing attached to the wall, a door controlling the opening from the chute inlet into the chute, a second door controlling the inlet into the chute inlet casing, pivot rods for the two doors about whose axes the doors respectively hinge, discs carried one by each door at adjoining ends of the doors and in the same planes, each disc being cut away through a space overlapped by the other in operation and means for mounting the discs rigidly with respect to the doors whereby, both doors being closed, opening movement of either door will cause its disc circumference to enter the path of movement of the other disc, preventing opening movement of the other disc.

4. In a chute inlet, a chute wall, an inlet casing thereto, a pair of doors controlling admission to the chute inlet and from it through the chute wall, rods about whose axes the respective doors swing, stiffening edges

for the doors extending beyond the axes, discs rigidly secured to the stiffening edges and adapted to oscillate around the axes of the respective rods, the discs overlapping and when one door only is open fitting the disc of the open door into an opening in the disc of the other door.

5. In a chute inlet, an inlet casing, a pair of cooperating doors therein supported to swing away from each other for opening movement of the doors, a pair of stops coaxially swinging, one with each door into the path of movement of the stop of the other door whereby each stop, when its door has begun opening movement bars opening movement of the stop of the other door, and a lever for opening one of the doors.

6. In a chute inlet, an inlet casing, a pair of cooperating doors within the casing supported to swing away from each other for opening movement of the doors, and a pair of stops swinging one with each door into the path of movement of the other door whereby each stop, when its door has begun opening movement, bars opening movement of the stop of the other door, each door being free to move by reason of pressure exerted upon the door itself when the other door is closed.

7. In a chute inlet, a casing having an inlet opening in substantially horizontal position and an outlet opening into the chute in substantially vertical position, a door closing the inlet opening and a door closing the outlet opening into the chute, the inlet door being adapted to be lifted by hand when the outlet door is closed and the outlet door being adapted to be opened by hand when the inlet door is closed and discs swinging with the two doors each recessed in the form of an arc permitting movement of the circumference of the other within the recess.
